L. H. ILLING,
CLEANING AND POLISHING MACHINE,
APPLICATION FILED AUG. 21, 1913.
1,160,613. Patented Nov. 16, 1915.

UNITED STATES PATENT OFFICE.

LEO H. ILLING, OF CHICAGO, ILLINOIS.

CLEANING AND POLISHING MACHINE.

1,160,613.

Specification of Letters Patent. Patented Nov. 16, 1915.

Application filed August 21, 1913. Serial No. 785,841.

To all whom it may concern:

Be it known that I, LEO H. ILLING, a citizen of the United States, and a resident of Chicago, county of Cook, and State of Illinois, have invented certain new and useful Improvements in Cleaning and Polishing Machines, of which the following is declared to be a full, clear, and exact description.

- 10 This invention relates to cleaning and polishing machines of that class adapted for cleaning and polishing knives, forks, spoons and the like, and has particular reference to the rotary brushes thereof which 15 perform the cleaning and polishing operation. Brushes of this kind are usually of ring like formation, the bristles projecting laterally from the ring; two brushes are employed in each machine and they are set 20 with the bristles of one brush opposing and contacting with those of the other brush. The brushes are revolved rapidly and the article to be cleaned and polished is inserted between them.
- 25 When sharp knives are operated on by the brushes, it frequently happens that the bristles are cut and often one or the other of the brushes is destroyed or damaged to such an extent that a new brush must be 30 substituted therefor. The brushes are somewhat expensive and the repairs are costly, due to frequent replacement of the brushes.

The principal object of this invention is to minimize the cost of repairs by providing 35 sectional brushes, in the form of segments which may be removed from and replaced by new ones when worn out or damaged.

Another object is to compensate for the 40 wear on the edges of the bristles of any section left in the machine when new brush sections are inserted to take the place of worn out or damaged ones.

To such ends the invention consists in the 45 several novel features hereinafter fully set forth and claimed.

The invention is clearly illustrated in the drawing furnished herewith, in which:

50 Figure 1, is a view of a cleaning and polishing machine embodying one form of the present invention, the view being partly in side elevation and partly in central vertical section; Fig. 2, is a view partly in end elevation and partly in vertical cross section, taken on the line 2—2 of Fig. 1, showing one of the brush sections partly broken

away and Fig. 3, is a perspective view of a brush section used in the machine.

Referring to said drawing, 10, designates a drive shaft mounted in bearing brackets 11, and carrying a pulley 12, arranged to be driven in any suitable manner as, for instance, by means of a belt running from any suitable sort of power. Mounted upon said shaft are two circular brush carrying heads 13, 13^a, the head 13, being fixedly secured to the shaft by means of a collar 14, fast on the shaft and having pins 15, which project into holes in the web 16, of the head. The other head 13^a, is slidably mounted on the shaft 10, and is spring pressed toward the fixed head 13, by means of a coiled compression spring 17, interposed between a collar 18, fast on the shaft, and the web 19, of the head 13^a.

75 The heads 13, 13^a, are designed to carry brushes which operate on the articles to be cleaned, and inasmuch as both brushes, and the means for connecting them to the heads, are substantially similar, a description of 80 one head and brush sections, carried thereby, will be sufficient so far as this specification is concerned.

85 Each brush carrying head is formed with an annular groove 20, between two concentric flanges 21, 22, that project laterally from the web 16, and said groove is adapted for the reception of the back of an annular brush 23. The brush comprises a plurality of segmental sections 24, 24^a, the backs 25, 90 of which seat in the groove 20, and have screw threaded pins 26, secured therein, which project out through holes 27, in the web of the brush carrying head. Said pins are secured in the backs 25, in any suitable 95 manner and they are here shown as provided with nuts 28, that are let into recesses in the sectional brush backs, and when screwed up tight against the backs, rigidly fasten the screw threaded pins to the back. 100 Nuts 29, are threaded upon the outer ends of the screw threaded pins 26, and bear against the outer face of the web 16, to secure the brush sections in place in the groove. The bristles 30, of the opposing 105 brush sections project toward each other and are pressed tightly together by the coiled compression spring 17. The bristles are grouped quite closely together so as to make a comparatively solid mass, the one 110 pressing against the other.

In Figs. 1 and 2, the brush section, desig-

nated by the reference numeral 24^a, is one whose bristles are shorter than the bristles of those shown in the other sections, such as would be the case if they had been worn down from considerable usage, and the other three worn out sections had been replaced by brush sections having full length bristles. To compensate for the difference in the length of the bristles, I provide washers 31, which may be interposed between the back of the old brush section and bottom of the groove in the brush carrying head, and these washers may be of different thicknesses so as to properly back up the brush section having the short length bristles, and thereby bring the ends of the bristles, or rather the working face of the section, flush with the working face of the bristles of the other sections. These washers may surround the screw threaded pins 26, if so desired, and by tightening up the nuts on the pins, this brush section may be properly secured in place, with its working face contacting with the working face of the opposite brush section.

In use, the shaft and brush heads and brushes carried thereby, are revolved, and if desired, cleaning and polishing powders may be applied to the brushes, after which the

article to be cleaned is inserted between the 30 contacting faces of the brushes and held there until the cleaning and polishing operation has been performed.

I realize that various alterations and modifications of this device are possible 35 without departing from the spirit of this invention and I do not therefore desire to limit myself to the exact details of construction shown and described.

I claim as new and desire to secure by Letters Patent:

In a cleaning and polishing machine, a rotary, disk-like, brush-carrying head, and an annular brush having a back piece and bristles secured therein and projecting therefrom in lines substantially parallel with the axis of rotation of said head, one of said members having studs fixedly secured thereto and projecting therefrom in lines parallel with said axis of rotation and the other member having holes for the reception of said studs whereby rotation of one member with respect to the other is prevented.

LEO H. ILLING.
